UNITED STATES PATENT OFFICE.

JOHANN VON HENTZEL, OF ZURICH, SWITZERLAND.

APPARATUS FOR HEATING LIQUIDS BY ELECTRICITY.

1,081,114.

Specification of Letters Patent.

Patented Dec. 9, 1913.

Application filed December 26, 1912. Serial No. 738,578.

To all whom it may concern:

Be it known that I, JOHANN VON HENTZEL, engineer, a subject of the Czar of Russia, residing at 12 Hornergasse, Zurich, Switzerland, have invented new and useful Improvements in Apparatus for Heating Liquids by Electricity, of which the following is a specification.

This invention relates to improvements in apparatus for heating liquids by electricity and more especially to electric water heating devices in which the water passes continuously through the space between two electrodes and serves as the resistance. In such electric heating devices, more especially when same are used by the medical profession, it is very important that the apparatus be perfectly safe in handling and that a simple regulation of the temperature and the water flow be obtainable.

The object of the present invention is to provide an apparatus which fulfills the above mentioned requirements. This is obtained by connecting the vessel which contains the electrodes and the water path between the electrodes directly with the water admission pipe and the water delivery pipe, these connections being electrically insulated, and by arranging the said vessel to be inclosed by an outer casing which carries the electrically insulated water admission and water delivery pipes, the outer casing being electrically insulated from the inner vessel.

The present apparatus does not require a separate device for regulating the temperature to which the water is heated since the adjustable flow of water is sufficient for regulating the temperature thereof.

In the accompanying drawings which show one construction of the invention, Figure 1 is a vertical section; Fig. 2 is a horizontal section on line A—B of Fig. 1; Fig. 3 is a side view and Fig. 4 is a plan view.

The improved apparatus comprises a cylindrical sleeve or shell 1 which is screw-threaded at the top and at the bottom and upon which are screwed two caps 2 and 3. The water is supplied through a central bore of the lower cap and is discharged from the apparatus through a central bore of the upper cap. The discharge pipe 8 for the hot water is insulated from the cap 2 by an ivory gland 2^a. The lower cap 3 has a lateral opening through which the cable 20 comprising the terminal wires is introduced.

an ivory gland 20^c serving for insulating the cable from the cap. A switch 20^b is arranged between the two wires.

The water is admitted to the apparatus by means of a connection piece 17 which passes through the central bore of the lower cap 3. This connection is provided with external screw threads 17^c by means of which it may be screwed directly into a water pipe or hose connected to a water supply, and 17^a is a washer for forming a tight joint at this point. The connection piece 17 is screwed into the cap 3 and is secured in position by means of a nut 17^a and a lock nut 17^b. The upper end of the connection 17 is also provided with screw threads to receive a flanged threaded sleeve 18 for connecting to the tube 17 to an inner water admission tube 11^b. For further securing the connection there may be provided a second flanged threaded sleeve 18^a, which engages the external threads on the sleeve 18 and a shoulder on the connection 17.

An ivory sleeve 19 and the two insulating washers 19^a and 19^b made of vulcanized rubber, or other suitable material, serve for insulating the pipe 11^b from the connection 17. The sleeve 1 is lined with a heat insulating material 4, such as asbestos, below which there is provided an electrical insulating silesth lining 5. The upper cap 2 is also lined with an asbestos layer 4^a and a silesth layer 5^a. Within these layers is arranged the sleeve 6 containing the electrodes which sleeve is closed by the bottom 11 and by the cover 6^a. The sleeve 6 is insulated from the shell 1 and the cap 2 by the above mentioned insulating layers both electrically and against heat transmission to the sleeve 1. Into the sleeve 6 is firmly pressed the outer hollow cylindrical electrode 15 and at a certain distance from the outer electrode is placed an inner electrode 16, which are preferably made of graphite. Between the two concentric electrodes there is therefore an annular space into which the water enters through the admission pipe 11^b and from which it is discharged by the delivery pipe 8. To the bottom piece 11 is fixed a terminal screw 11^c which serves for supplying the electrical current, while the copper eye 14^a serves as the second terminal.

Through the center of the sleeve 6 passes a central bolt 12 fixed to the bottom 11, the upper end of which is screw-threaded at 12^b and serves for securing the electrode 16.

The water delivery pipe 8 is further insulated by an ivory sleeve 10 arranged between the delivery pipe and a connecting nut 7. The lower end 12^d of the central bolt 12 carries the disk 12^a upon which the electrode 16 is supported. Underneath the disk 12^a there is a mica plate 13 and underneath the latter a plate of vulcanized rubber 13^a for the purpose of providing electrical insulation between the bottom 11 of the vessel and the central bolt 12. This arrangement is supported by a nut 12^e secured upon the lower end 12^d of the rod 12.

13^b is an ivory ring which insulates the bottom 11 from the central rod 12, while 13^c is a rubber disk and 14 is a thin brass disk, the disk 13^c serving as an electrical insulation.

The water discharge pipe 8 is connected 20 to the cover 6^a by means of the nut 7. Between the flange 8^a of the discharge pipe and the nut 7 there is arranged a disk 9 of vulcanized rubber and a similar disk 9^a is arranged underneath the flange 8^a of the pipe 8. Through the flange 12^a, and the insulating disks 13 and 13^a a free space is provided between the bottom 11 and the electrode 16 so that the electrode 16 is perfectly insulated from the bottom. The apparatus 25 may also be provided with an adjustable base in which the water admission and, if necessary, the water regulating valve, may be arranged.

I claim—

- 35 1. Apparatus for heating liquids by electricity comprising an outer cylindrical casing, an insulated layer within said casing, a closed cylindrical casing within said first casing but insulated therefrom, a central rod 40 extending through one end of second chamber but insulated therefrom, a cylindrical electrode mounted on said rod, a hollow elec-

trode surrounding said first electrode and pressed against the internal surface of the inner casing, electrical connections one to 45 said rod and one to said inner casing, and means for causing water to flow through the space between said electrodes and serve as a resistance, substantially as described.

2. Apparatus for heating liquids by electricity comprising an outer cylindrical casing, closure caps at each end of said casing, a heat insulating layer within said casing and within one of said closure caps, an electrical insulating layer within said heat insulating layer, a closed cylindrical casing inside said first casing but insulated therefrom, a central rod extending through one end of said inner casing but insulated therefrom, a cylindrical electrode mounted on 50 said rod, a hollow electrode surrounding said first electrode, and pressed against the internal surface of said inner casing, an annular space between said electrodes, an annular chamber between each end of the electrodes and the ends of said inner casing, electrical connections one to said rod and one to said inner casing, a water delivery pipe carried by first chamber but insulated therefrom and leading to one of the said annular 55 spaces, and a discharge pipe insulated from both casings and leading from the other of said annular spaces, said discharge pipe passing through the closure cap provided with said heat insulating layer; substantially as 60 described.

In testimony whereof I, have signed my name to this specification in the presence of two subscribing witnesses.

JOHANN von HENTZEL.
